VENTILATOR

Fred P. Darnell, Chesterland, and Walter J. Skipworth, Wickliffe, Ohio, assignors, by mesne assignments, to Swartwout Fabricators, Inc., Kokomo, Ind., a corporation of Indiana

Filed July 29, 1957, Ser. No. 674,667

7 Claims. (Cl. 98—86)

Our invention relates to roof ventilating apparatus or valves and more particularly to normally closed roof valves, which are adapted to open and vent the interior of the building in response to predetermined changes in conditions within buildings.

The desirability of rapidly and automatically or manually opening large roof areas, upon the outbreak of fire and explosion, for example, has long been recognized, in order to vent the smoke, heat and/or explosive force so as to make the fire visible to the firefighters, to control the temperatures within the building, to free the building from noxious gases and/or to preserve the building against explosive force.

Various apparatus have been developed to accomplish one or more of these objectives but each has been deficient in some respect and all have failed to provide the protection and advantages, which the art has wanted and demanded. Further, the widespread adoption of large, relatively low, single story factory buildings has accentuated the need for efficient, acceptable apparatus of this type, albeit without suggesting or indicating how the desired results could be obtained and what the embodiment of such apparatus should be.

It is a general object of our invention to provide an improved, efficient, economically manufactured and used, rugged and substantially foolproof roof ventilator for closing roof openings, which is adapted to open and vent the interior of the building in response to predetermined changes in conditions within the building.

A further object is to provide a roof ventilator, adapted normally to close a roof opening, which opens automatically in response to fire, heat and/or explosion, to vent, *inter alia*, smoke, heat, gas and/or pressure and which is or may be adapted to be operated manually, either from within the building or from without the building on the roof thereof.

Other objects of our invention are the provision of a single roof ventilator for a roof opening which is adapted to be used both to vent the building under ordinary conditions and to provide emergency ventilating facilities for ventilating the building of smoke, heat, and/or pressure; which may be either automatically or manually actuated; which is economically produced, easily installed, ruggedly constructed, completely fireproof and substantially foolproof in use and operation; which quickly opens automatically in response to predetermined temperatures and/or pressures; which opens to provide a maximum free exhaust path through which gases, heat, and smoke can escape from the interior to the exterior of the building; which is weatherproof; which when open promotes the eduction of smoke and gases from the building and effectively shields and protects the exhaust flow from wind currents and the like.

These and other objects and advantages of our invention will become apparent from the following description of preferred embodiments thereof, reference being had to the accompanying drawings, in which:

Figure 1 is a perspective view, with one damper open

2

and the other removed, of a roof ventilator embodying a preferred form of our invention.

Figure 2 is a sectional view of the ventilator of Figure 1 taken along the line 2—2 of Figure 1 and showing both dampers in the closed position, in full lines, and in an open position, in dotted lines.

Figure 3 is a broken plan view of the ventilator of Figure 1 with both dampers removed and certain parts broken away to show the operating mechanism.

10 Figure 4 is a section viewed along the lines 4—4 of Figure 1 showing the hinge by which the dampers are mounted on the body of the ventilator.

Figure 5 is a perspective view, with certain parts broken away and others omitted, showing another preferred form of operating mechanism in the ventilator of Figure 1.

Figure 6 is a schematic view showing the mechanism of Figure 5, closed, in full lines, and partly opened, in dotted lines.

20 Figure 7 is a fragmentary sectional view, on an enlarged scale, showing the means for releasably securing the dampers to the damper actuating means.

A roof ventilator or valve embodying a preferred form of our invention is adapted normally to close a roof opening and is further adapted to give instantaneous and automatic relief to predetermined increases in pressures and temperatures within the building to the end of reducing the deleterious effects which fire, explosion and/or heat accumulations may or do have on the building and its contents, and to be manually operable from within or without the building to open fully and quickly, either for emergency purposes or as an ordinary roof ventilator.

Further our ventilator is adapted to be weatherproof when closed and to aid and expedite the eduction of gases from within the building to the exterior thereof, when open, by protecting the path of the educted gases from cross winds and other adverse wind currents.

Briefly a ventilator embodying a preferred form of our invention, see Figures 1 and 2, comprises a supporting structure indicated generally at 1, having a generally triangular transverse section and supporting a pair of dampers 3 and 4, respectively, each of which is hinged to the supporting structure 1 and is adapted to be opened, on the one hand, by hinged, powered damper carriers or actuating or operating members indicated generally at 6 and 9 respectively, when the same are released, and on the other hand, independently of the members 6 and 9 when acted upon by a direct lifting force. The members 6 and 9 are adapted to be actuated in response to predetermined changes in conditions within the building and/or manually by an operator.

More particularly the supporting structure 1 preferably comprises a generally rectangular base 12 formed from corrosion resistant sheet metal and adapted to fit over and be secured or anchored to a curb or other mounting provided on the roof of the building and surrounding an opening therein. The base 12 preferably comprises parallel, elongated sides 13 and 14, preferably having longitudinally extending horizontal or stepped portions 15 and 16, respectively, and parallel, generally triangularly shaped end pieces 17 and 18. The sides and end pieces are secured together at their respective junctures, as by welding, to form a weatherproof vertical guard about the roof opening. The upper edges of the end pieces 17 and 18 slant upwardly and inwardly from the upper edges of the respective sides and provide a stop or rest for supporting the dampers 3 and 4 when the same are in the closed position. A brace 19, conveniently formed from an angle iron, extends between and interconnects the end pieces 17 and 18 near their apexes and gives structural strength to the upper portions of the ventilator as well as support for the actuating members' releasing

mechanism, and angles 21 (see Figure 4) and 22 are secured to and extend transversely of the interior lower portions of the end pieces 17 and 18 respectively.

The stepped portions 15 and 16 and angles 21 and 22, not only provide structural strength for the respective sides and ends, but also are adapted to seat upon and be fastened, by suitable fasteners, not shown, to the curb surrounding the roof opening, to the end that the entire ventilator is easily and expeditiously positioned and secured in place.

The supporting structure 1 also preferably includes angle braces 24 and 25, which are secured to the brace 19 and the mounting angles 21 and 22 respectively, and a channel brace 27, which is secured to and extends between the lowermost portions of the sides 13 and 15 respectively to provide additional structural strength to and for the ventilator.

Each of the dampers 3 and 4 preferably comprises a generally concavo-convex main body portion 28 having an angled bottom flange 36, which overlies and overlaps the upper edge of the respective sides 13 and 14, and an angled top flange 31, which is adapted to mutually overlap and overlie or underlie the similar flange of the other damper when the ventilator is closed. The mutually overlapping flanges 31 form a weather-proof peak and further cooperate so that the ventilator functions with equal facility and advantage without regard to which damper 3 or 4 is closed first or is topmost along the overlap.

Additionally, each of the dampers 3 and 4 is provided with side flanges 33 and 34, respectively, which extend perpendicular to the body portion 28 thereof and overlie and overlap the top edge of the adjacent end pieces 17 and 18 respectively. Thus the dampers when closed completely weatherproof the roof opening.

The dampers 3 and 4 are adapted to open and close relative to the ventilator and roof opening and in response to predetermined actuating forces, as will hereinafter more fully appear, and to this end are hinged or pivotally mounted on the supporting structure 1 of the ventilator, about an axis extending longitudinally of the ventilator.

Preferably and conveniently each damper is pivotally mounted on the ventilator by suitable engagement between the lower opposite ends of the damper and damper supporting means carried by and secured to the respective end pieces of the ventilator. More particularly each damper supporting means preferably comprises a stud or shoulder rivet 36 (Figure 4), which is suitably positioned on and secured to the adjacent end piece, 17 for example, and extends longitudinally outwardly therefrom, and a conveniently disk or cup-shaped spacing and pivot member 37, which functions to space the end of the damper from the ventilator end piece, to brace or support the stud 36 a spaced distance from the end piece and to provide a better and more efficient pivot surface for the swinging of the damper. The stud 36 preferably has a shoulder 39 against which the pivot member 37 bears and by which the cupped portion of the pivot is properly spaced from the ventilator end piece. The rim or edge of the pivot member 37 is secured to the adjacent end piece as by rivets 40. The free end of the stud projects through and has rotatable engagement with a suitable aperture 41 provided in the adjacent side flange of the damper, 33 for example. Preferably a washer 42 is disposed about the stud between the member 37 and the side flange and an aperture reinforcing plate 43 is secured to the side flange and adapted to engage about the stud 36 in the same manner as aperture 41.

The damper actuators 6 and 9 are a part of a damper operating or actuating mechanism indicated generally at 46 (Figure 1) which is adapted to respond automatically to predetermined conditions within the building or selectively, at the will of the operator, to raise the dampers and open the ventilator.

Briefly (see Figures 2 and 3), the mechanism 46 com-

prises, in addition to the members 6 and 9, a source of force or power such as torsion springs 47 and 48 together with means to control the power source, such as means to set and means to release the springs, and means 5 to transmit the released force and motion to the members 6 and 9 and thereby to the dampers to raise them and open the ventilator.

More particularly and preferably the damper actuating mechanism includes a pair of parallel, vertically extending, longitudinally spaced brackets 49 and 50, which are secured to the underside of the top brace 19 near the midpoint thereof and which fixedly support a rod or shaft 52 extending therebetween. In order that the one end of each spring 47 and 48 may be fixedly anchored and in order that the tension of the springs may be varied at the discretion of the user, I preferably mount a pair of fixed, though adjustable, collars 53 and 55 about the shaft near the opposite ends thereof. The springs 47 and 48 are then disposed about the shaft 52 between the collars 53 and 55, with one end of spring 47 secured to the collar 53 and one end of the spring 48 secured to the collar 55. The opposite ends of the respective springs are preferably secured to collars 56 and 58, which are rotatably supported on the shaft 52 and which are secured to or formed integral with crank arms or damper operator angles 59 and 60, respectively (Figure 2). A washer 61 (Figure 3) may be disposed between the collars 56 and 58 when, as we prefer, the same are otherwise adjacent each other.

10 Damper operating levers 63 and 64 (Figure 2) are pivotally secured to the crank arms 59 and 60 respectively near the ends thereof remote from the collars 56 and 58 and are in turn pivotally secured to the damper actuating members 6 and 9 respectively. The crank arms 59 and 60 function to transmit the force and motion of the springs 47 and 48 to the members 6 and 9 and may if desired be integral extensions of the respective ends of the springs 47 and 48 remote from the collars 53 and 55.

15 Preferably each of the actuating members 6 and 9 comprises a pair of longitudinally spaced, parallel angles or similar members 66 and 67 (Figure 3), which are rotatably supported or hinged, adjacent the top of the respective sides of the ventilator, substantially in longitudinal alignment with the respective damper hinges, as by being 20 rotatably mounted on the respective rods or shafts 68, which are in turn mounted on the brace 27 at the upper ends thereof. Each of the actuating members 6 and 9 also preferably includes a cross member or brace 69, which lies near or adjacent the brace 19 when the actuating member is in the down (closed) position and which 25 adds structural strength thereto and maintains the members 66 and 67 in longitudinal alignment.

30 The springs 47 and 48 exert a torque on the collars 56 and 58 which tends to rotate the respective collars 35 and crank arms 59 and 60, unless the same are secured against rotation, and to extend the arms outwardly in opposite direction (to the right and left, respectively, as viewed in Figure 2). When so rotated the crank arms, in cooperation with the hinged actuating members 6 and 35 9, move the levers 63 and 64 into mutual lengthwise alignment respectively to the end that the members 6 and 9 are displaced and moved so as to lie in substantially vertical planes, i.e., extend upwardly, as viewed, from the respective shafts 68 and as the members 6 and 9 40 are so rotated and displaced they similarly rotate and displace the dampers 3 and 4, which they respectively support, thereby opening the same.

45 Thus when the dampers 3 and 4 are closed the actuating members 6 and 9 are forced down tensioning the 50 springs 47 and 48 and the dampers 3 and 4 and actuating members 6 and 9 must be held closed against the force of the springs 47 and 48. Therefore the actuating mechanism 46 includes means to secure the dampers and actuating members in the closed position against the force 55 of the springs. Such means is adapted to release the

damper actuating mechanism either in response to manual actuation or automatically in response to predetermined changes within the building and preferably in response to a rise in temperature within the building.

To this end we provide means interconnecting and mutually restraining the crank arms 59 and 60 against rotative movement and means to sever, release or oppose said restraining means in response to predetermined stimuli.

Such means preferably includes a release lever 70 (Figure 2), at the lower end of one of the crank arms, 60 for example, and a pin 72 at the lower end of the other crank arm. The lever 70 extends transversely of the ventilator and is pivotally secured to the crank arm 60. One end of the lever 70 is disposed adjacent the crank arm 59 and is bent or otherwise provided with a hook, as at 73, which is adapted to engage the pin 72 so as to be able to prevent the arms 59 and 60 from rotating, under the influence of the springs 47 and 48, outwardly in opposite directions relative to each other in the manner described above. However, the springs 47 and 48 acting through the arms 59 and 60 exert sufficient force, unless opposed, to cause the pin to displace the lever 70 and hook 73 upwardly about the pivotal axis of the lever 70 thereby to release the crank arms and actuating mechanism to open the dampers.

Accordingly our actuating mechanism includes means for releasably opposing the force of the torsion springs to maintain the members 6 and 9 closed as well as means to relieve this opposing force in order to permit the springs 47 and 48 to operate to raise the members 6 and 9 and open the dampers. To this end the release lever 75 preferably extends about the same distance in both directions from the arm 60 and an upward counter force is exerted on the free end 75, leftward end as viewed in Figure 2, of lever 70 to maintain the hook 73, righthand end of lever 70, as viewed, in engagement with pin 72. This counter force may be opposed manually by pulling down on chain 76, which depends from end 75 of lever 70 and has its free end within the reach of an operator.

Preferably this counter force is exerted by means of a spring 77, which is mounted in a chain or similar member 78, one end of which is secured to the end 75 of the lever 70 and the other end of which is adjustably secured to the brace 19 as by passing through an aperture in the horizontal portion thereof and thence through a bifurcated keeper 79. Thus, by pulling on the chain 78, the operator tensions the spring 77 until a sufficient force is exerted thereby on the lever 70 to oppose the force of the torsion springs 47 and 48 and the force so exerted is maintained on the lever 70 by engaging the tensioned chain in the keeper 79. If desired a link of the chain 78 may be painted or otherwise marked so that the operator need only catch said link in the keeper to insure that the spring 77 is under proper tension.

When, as we prefer, the release means herein described is adapted to respond only to a predetermined high temperature and not to a predetermined increase in pressure, a fusible link 81, having a predetermined melting point, is positioned in the chain 78 between the lever 70 and the brace 19. Thus if and when the temperature within the building and about the link rises to the predetermined degree the link fuses, breaking the chain and disconnecting the force of spring 77 from the lever, thereby permitting the torsion springs 47 and 48 to open the dampers in the manner described above.

Further, the operator may also selectively manually open the dampers from within the building by simply pulling on the chain 76 with a force sufficient, in combination with the force of the torsion springs 47 and 48, to overcome the force of spring 77 and raise the hook 73 out of engagement with the pin 72 whereupon the dampers open in the manner described above.

Since the dampers 3 and 4 are hinged independently of the actuating members 6 and 9, the dampers 3 and 4

may open independently of the actuating members 6 and 9 if a sufficient upwardly directed force be exerted there-in, such as might result from an explosion within the building. In order to predetermine the amount of force necessary to so open the dampers and to provide means whereby the respective dampers and actuating members may function as a unit when the actuating mechanism is operated, a ventilator embodying a preferred form of our invention preferably includes means for releasably securing the dampers 3 and 4 to the respective actuating members 6 and 9. Preferably such means comprises a plurality of ball and stud spring fasteners or catches indicated generally at 84, Figure 2, mounted with one member secured to the cross members 69, for example, and the other member secured to the respective dampers so as to be in operable relation with the first member. Conveniently the spring stud 84' of each fastener 84 is mounted on the underside of the respective cross members 69 concentrically with an aperture 85 (Figure 3) provided in the member 69 and the ball 84" of each fastener 84 is mounted on the respective damper and is adapted to engage the stud by passing through the aperture 85. When the pressure within the building increases to a predetermined level it exerts a sufficient force on the dampers to separate the balls 84" from the spring studs 84' and to open the independently hinged dampers while the actuating members 6 and 9 remain in the closed position.

Preferably handles 86 (Figures 1 and 2) are mounted on the upper exterior portions of the dampers so that the same may be opened from above by a person lifting thereon with sufficient force to disengage the spring catches 84 and safety chains 87 having springs 88 there-in extend between the braces 24 and 25 and the respective dampers to restrain the dampers against opening too far.

In use and after installation, the ventilator is set by positioning the crank arms 59 and 60 and release lever 70 and then pulling on the chain 78 until the proper tension is applied and positioning the same in the keeper. The dampers, if not already closed, are then slammed shut so that the spring catches 84 engage and the ventilator is ready for use. The ventilator may then be manually operated and opened as desired and needed by pulling on chain 76 or lifting on the handles 86, or automatically opened in response to a predetermined increased pressure, such as might follow an explosion, acting upon and lifting the dampers, or a predetermined increased temperature, such as might follow a fire, fusing the link 81 and releasing the lever 70. Once opened the dampers are closed and if needed the operating mechanism 46 is reset in the manner set forth and the ventilator is ready for another cycle. Thus it is evident that we have provided a simple, rugged, foolproof and efficient ventilator or roof valve which accomplishes the objects of our invention and provides complete and rapid emergency venting to and for a building upon which it is mounted as well as having the facility and utility of operation incident to providing discretionary interior and exterior manual actuation.

Another preferred form of actuating mechanism for a ventilator embodying our invention is illustrated in Figure 5. The actuating mechanism disclosed in Figure 5 is adapted to be mounted in a ventilator which, conveniently, is in all respects otherwise similar to the ventilator illustrated in Figures 1 through 4. In this alternate form of actuating mechanism the brackets 49 and 50, shaft 52, brace 27 and actuating members 6 and 9 are substantially similar to the corresponding parts of the actuating mechanism shown in Figures 1 through 3 and the torsion springs 47' and 48' provide the force and power necessary to operate the mechanism and open the dampers. The springs 47' and 48' are mounted on the shaft 52 and are similar to the springs 47 and 48 except that one end of each extends substantially radially outwardly or tangential therefrom and from the shaft 52, in

a manner similar to the crank arms 59 and 60. U-shaped elbow locks 91 and 92 are mounted on the respective radially extending ends of the springs 47' and 48' in axial extension thereof. Damper operating levers 63' and 64' are pivotally secured to the respective elbow locks 91 and 92 and actuating members 6 and 9. Conveniently the levers 63' and 64' have a bifurcated outward end which is mounted on a pin or shaft 93, which extends between the respective angles 65 and 67 in order to form a yoke type linkage between levers 63' and 64' and members 6 and 9 respectively.

In order to oppose the force of the springs 47' and 48' and restrain the actuating mechanism against opening the dampers except in response to predetermined changes in conditions within the building upon which the ventilator is mounted or at the discretion of the operator we preferably mount a bracket 95 on the cross brace 27' at the center thereof. Z-type hinges or latches 96 and 97, respectively, are pivotally mounted on the bracket 95 and extend toward the respective sides of the ventilator. The hinges 96 and 97 are adapted to engage the respective elbow locks 91 and 92 to restrain the outward rotary movement of the radially extending ends of the springs 47' and 48' in substantially the same manner and for the same purpose that the release lever 70 and pin 72 restrain the movement of the crank arms 59 and 60. The hinges 96 and 97 are maintained in engagement with the respective elbow locks by the tension springs 77', which are secured to the respective hinges 96 and 97 and are properly tensioned by means of the chain 78'.

The chain 78' also includes a fusible link 81 and the chain 78', springs 77' and link 81 function in substantially the same manner and for the same purpose as the chain 78, spring 77 and fusible link 81 described above. A keeper (not shown) is provided for engaging the chain 78' and maintaining the tension on the springs 77'. Our alternate form of actuating mechanism is also preferably provided with a branched chain 76' in order that discretionary manual release of the actuating mechanism may be effected.

Rollers 98 are preferably mounted at the lower outer corners of the elbow locks 91 and 92 to facilitate the disengaging of the respective Z hinges and elbow locks upon actuation of the operating mechanism.

In a ventilator embodying our invention a greater effective force must be exerted upon the dampers, and therefore the damper actuating members 6 and 9, to initiate the opening of the dampers than is necessary to complete the displacement of the dampers to the fully open positions. This greater force is necessary not only because of the inertia of the closed dampers but also because the inclined position of the closed dampers causes the weight thereof to act through a longer moment arm (W-1, Figure 6) than at any other time during the movement thereof (W-2, Figure 6, for example) and accordingly a greater counterforce is necessary, initially, to initiate movement of the dampers.

Therefore actuating mechanism embodying this form of our invention preferably also includes means to vary the effective length of the free end of the torsion springs (i.e. end 100 of spring 92, for example, Figures 5 and 6) so that the moment arm through which the dampers oppose the force of the respective torsion springs is less initially, upon actuation of the operating mechanism, than after movement of the damper has been initiated. The elbow lock 92, spring end 100 and damper operating lever 64' are so adapted that the elbow lock functions initially as an integral part of the operating lever and after movement of the damper is initiated as part of the crank arm i.e. spring end 100. Thus the moment arm through which the damper initially opposes the force of the torsion spring is foreshortened M-1, Figure 6, from what it is M-2 Figure 6 after movement of the damper has been initiated.

To this end stops 101 are welded or otherwise secured to either side of the damper operating levers and are adapted to extend therefrom and engage and clamp against the respective edges of the adjacent elbow lock 92, for example displacing the elbow lock rightwardly as viewed in Figure 6, about the pivot P between the elbow lock and the operating lever.

We also provide an aperture or hole 102 in the base 103 of the elbow lock and an elongated transverse slot 105 in one face of the elbow lock and the free end 100 of the torsion spring extends through aperture 102 and is bent so as to extend through and engage within slot 105.

The hole 102 is of slightly larger diameter than the end 100 of the spring and the hole 102 and slot 105 are disposed relative to each other as to cause an engagement at E between the spring and 100 and the base 103 of the elbow lock when the damper is closed and the stops 101 engage the elbow lock. Thus the elbow lock and operating lever function as an integral unit, while the damper is initially actuated by and upon the release of the operating mechanism, to foreshorten the moment arm as indicated by M-1 Figure 6.

Once the movement of the damper is initiated, however, the stops 161 are displaced relative to elbow lock so as to disengage the same whereupon the spring end 100, elbow lock and operating lever 64' take the relative positions shown, for example, in dotted lines in Figure 6 and the elbow lock functions as an extension of the spring end (crank arm) and the moment arm is the distance M-2 between the torsion spring and the pivot P. It is, of course, necessary that the pivot P be between the elbow lock and the operating lever otherwise be at point P in order that the combined length of the spring end 100, elbow lock 92 and operating lever 64' (for example) is sufficient, when fully extended, to hold the dampers in the desired fully open position.

The preferred form of the alternate actuating mechanism embodying our invention is adapted to respond to the same or similar stimuli as the first described actuating mechanism embodying our invention to open the dampers 3 and 4 in substantially the same manner as the first described actuating mechanism, except that a relatively greater force is exerted on the dampers to initiate the movement thereof than is exerted thereon to maintain the movement because the interrelation and action of the damper operating levers 62' and 64', stops 101, elbow locks 91 and 92 and spring ends as set forth above.

Modifications, changes and improvements to the above described and illustrated preferred forms and embodiments of our invention may occur to those skilled in the art without departing from the spirit and substance of our invention. Accordingly we do not wish to be limited in the scope of our patent to the forms and embodiments of our invention herein described nor in any member inconsistent with the advance by which our invention has promoted the art.

We claim:

1. A roof ventilator comprising a base defining a ventilator opening and adapted to be mounted over a roof opening in a building, a pair of opposed dampers adapted to close said ventilator opening and pivotally mounted on said base for outwardly hinged movement relative to said ventilator opening about parallel axes, and damper actuating means for actuating said dampers, said damper actuating means including damper actuating members supported on said base with one said damper actuating member being in operable relation with each said damper, respectively, each said damper actuating member being pivotally supported on said base for rotation about an axis extending parallel with said damper axes, having closed and open positions and engaging said respective damper to open it, said damper actuating means also including torsion spring means carried by said base, a pair of crank arms operably connected with said torsion spring means, lever means pivotally con-

nected to each said crank arm remote from said torsion spring means and pivotally connected to said damper actuating members, respectively, and adapted to transmit motion from said crank arms to said damper actuating members, respectively, said torsion spring means biasing said crank arms for rotation in opposite directions about said torsion spring means and away from each other when said actuating members are in said closed position, means adapted to engage said crank arms, to restrain said crank arms against rotation away from each other, spring means restraining, and biasing said restraining means into engagement with said crank arms, fusible link means in said spring means and responsive to a predetermined temperature to sever said spring means and release said restraining means to permit said crank arms to open said actuating members and dampers, and manual release means for selectively opposing and relieving said spring means to release said restraining means to permit said crank arms to open said actuating members without severing said spring means.

2. The ventilator according to claim 1 in which said restraining means comprises a lever pivotally secured to one said crank arm and releasably engaging the other said crank arm and said spring means acts between said lever and said base to urge said lever into engagement with said other crank arm.

3. A roof ventilator comprising a base defining a ventilator opening and adapted to be mounted over a roof opening in a building, a pair of opposed dampers adapted to close said ventilator opening and pivotally mounted on said base for outwardly hinged movement relative to said ventilator opening about parallel axes, and damper actuating means for actuating said dampers, said damper actuating means including damper actuating members supported on said base with one said damper actuating member being in operable relation with each said damper, respectively, each said damper actuating member being pivotally supported on said base for rotation about an axis extending parallel with said damper axes having closed and open positions and engaging said respective damper to open it, said damper actuating means also including torsion spring means carried by said base, a pair of crank arms operably connected with said torsion spring means, lever means pivotally connected to each said crank arm remote from said torsion spring means and pivotally connected to said damper actuating members, respectively, and adapted to transmit motion from said crank arms to said damper actuating members respectively, said torsion spring means biasing said crank arms for rotation in opposite directions about said torsion spring means and away from each other when said actuating members are closed, latch means carried by said base and engaging said crank arms, respectively, to restrain said crank arms against rotation away from each other, and release means including spring means acting between said base and said respective latch means and biasing said latch means into engagement with said crank arms, respectively, fusible link means responsive to a predetermined temperature to sever said release means to disengage said latch means and release said crank arms to open said actuating members and dampers, and manual release means for selectively opposing and relieving said spring means to disengage said latch means and release said crank arms to open said actuating members without severing said release means.

4. The ventilator according to claim 3 with means responsive to a predetermined outwardly directed force releasably securing each said damper to the respective damper actuating member.

5. The ventilator according to claim 3 in which said

release means includes chain means secured to each said manual latch and operable to oppose the force of said spring means.

6. The ventilator according to claim 3 in which said base includes a chain keeper, said spring means comprises two springs and said release means also includes chain means, each said spring having one end secured to a respective latch means and the other end secured to said chain means, said chain means being adapted to engage said keeper to maintain a tension on said springs and said fusible link means being disposed in said chain means.

7. A roof ventilator comprising a base defining a ventilator opening and adapted to be mounted over a roof opening in a building, a pair of opposed dampers adapted to close said ventilator opening and pivotally mounted on said base for outwardly hinged movement relative to said ventilator opening about parallel axes, and damper actuating means for actuating said dampers, 15 said damper actuating means including damper actuating members supported on said base with one said damper actuating member being in operable relation with each said damper, respectively, each damper actuating member being pivotally supported on said base for rotation about an axis extending parallel with said damper axes, having closed and open positions and engaging said respective damper to open it; said damper actuating member also including torsion spring means carried by said base, a pair of crank arm means operably connected 20 with said torsion spring means, lever means pivotally connected to each said crank arm means remote from said torsion spring means and pivotally connected to said damper actuating members, respectively, and adapted to transmit motion from said crank arm means to said 25 damper actuating members, respectively, said torsion spring means biasing said crank arm means for rotation in opposite directions about said torsion spring means and away from each other when said actuating members are closed, means restraining said crank arm means 30 against rotational movement away from each other, and release means to relieve said restraining means, said crank arm means comprising elbow lock means mounted on each said crank arm means adjacent the end thereof remote from said torsion spring means for limited pivotal motion relative to said crank arm means in the plane in which said crank arm means rotate, each said lever means being pivotally connected to said elbow lock means, respectively, stop means mounted on each said lever means and adapted to engage said elbow lock 35 means respectively nearer said torsion spring means than said pivotal connection between said lever means and said elbow lock means and pivotally displacing the adjacent portion of said elbow lock means to engage said crank arm means nearer said torsion spring means than said pivot between said elbow lock means and said lever means when said damper actuating member is in a closed 40 position.
